US00D920264S

(12) **United States Design Patent** (10) **Patent No.:** **US D920,264 S**
(45) **Date of Patent:** **** May 25, 2021**

(54) **SEMICONDUCTOR DEVICE**

(71) Applicant: **THE NOCO COMPANY**, Glenwillow, OH (US)

(72) Inventors: **James P. McBride**, Phoenix, AZ (US); **James Richard Stanfield**, Peoria, AZ (US)

(73) Assignee: **THE NOCO COMPANY**, Glenwillow, OH (US)

(**) Term: **15 Years**

(21) Appl. No.: **29/715,103**

(22) Filed: **Nov. 27, 2019**

(57) **CLAIM**

The ornamental design for a semiconductor device, as shown and described.

DESCRIPTION

FIG. 1 is a perspective view of a semiconductor device showing our new design;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.
